COMBINED ROOM DIVIDER AND BUFFET OR SIMILAR ARTICLE

Alexander C. Challis, Cherry Hill, N.J.
(Box 294, Maple Shade, N.J.)

Filed July 1, 1963, Ser. No. 75,590

Term of patent 14 years

(Cl. D33—19)

FIGURE 1 is a front perspective view of a combined room divider and buffet or similar article, showing my new design;

I claim:
The ornamental design for a combined room divider and buffet or similar article, as shown and described.
